UNITED STATES PATENT OFFICE.

LOUIS H. MANSON, OF CHICAGO, ILLINOIS.

DESIGN FOR A BICYCLE-FRAME.

SPECIFICATION forming part of Design No. 30,415, dated March 28, 1899.

Application filed November 22, 1898. Serial No. 697,198. Term of patent 7 years.

To all whom it may concern:

Be it known that I, LOUIS H. MANSON, a citizen of the United States, residing at Chicago, in the county of Cook and State of Illinois, have invented and produced a new and original Design for Bicycle-Frames, of which the following is a specification, reference being had to the drawings, forming a part thereof.

10 Figure 1 is a perspective representation of a bicycle-frame embodying the features of my invention. Fig. 2 is a cross-section through the forks A or D about midway of their length.

As shown in the drawings, the leading or 15 material features of my design consist in the configuration of a bicycle-frame, wherein the lower rear forks A, extending from the axle of the rear wheel to the crank-hanger B, are united in a single tube or stem C, which tube

or stem rigidly unites the fork-crown A' with 20 said crank-hanger B, and, further, wherein the upper rear forks D, extending from the axle of the rear wheel to the seat-post bracket E, are united in a single tube or stem F, which tube or stem rigidly connects the fork-crown 25 D' with the said seat-post bracket E.

The forks A and D are substantially of irregular octagonal form in cross-section, the inside face of each fork-arm being considerably broader than any of the other surfaces 30 thereof.

I claim as my invention—

The design for a bicycle-frame, substantially as herein shown and described.

LOUIS H. MANSON.
